[57] **CLAIM**

The ornamental design for a fan speed and light dimmer controller, as shown and described.

DESCRIPTION

FIG. 1 is a perspective view of a fan speed and light dimmer controller taken from above and side showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is a rear and lower left perspective view thereof.
